UNITED STATES PATENT OFFICE.

WILLIAM BORCHERT AND FRED L. BORCHERT, OF ROCKFORD, ILLINOIS, ASSIGNEES
TO THE TAGIT COMPANY, OF ROCKFORD, ILLINOIS, A CORPORATION OF ILLINOIS.

STAPLE-TAG-AFFIXING MACHINE.

Application filed October 29, 1920. Serial No. 420,419.

To all whom it may concern:

Be it known that we, WILLIAM BORCHERT and FRED L. BORCHERT, citizens of the United States, residing at Rockford, in the 5 county of Winnebago and State of Illinois, have invented certain new and useful Improvements in Staple-Tag-Affixing Machines, of which the following is a specification.

This invention has reference to machines 10 particularly adapted for affixing staple tags to flat material. These tags are used in laundry tags and other places for marking and identification purposes. Staple tags well known to the laundry trade, are characterized by their rectangular fabric body 15 equipped at each end with a pair of metallic spurs or staples which are pressed through the goods and clinched under to fasten the tag to the goods. The fabric body between the spurs is used for marking. These tags are frequently put on by hand, that is, the spurs are pressed through the goods and clinched under by hand. Mechanical devices have also been employed for 20 attaching these tags; but in many instances the means employed have been unsatisfactory for the reason that tags are not securely attached and the spurs are not properly clinched, and in many instances the points 25 project and are a source of danger.

One of the primary objects, therefore, of the present invention is to provide a simple machine for so attaching staple tags and the like to flat material that they will be firmly 30 secured thereto with the points of the spurs turned under and embedded in the goods so as not to scratch or mar.

Another important object is the provision 35 of a novel machine for affixing staple tags by a simple hand pressure movement.

We have also aimed to provide a staple 40 tag-affixing machine so constructed that the operator places a tag in a holding device; then positions the goods or other material 45 over an anvil; and then by pressure by the hands holding the goods, causes the tag in said holding device to be clinched to the goods.

Still another object resides in the provision 50 of a hand-operated lever-carrying anvil over which the goods to be tagged is placed, and in the provision of a tag carrier and a hammer both actuated by movement of the hand lever, the former for

properly positioning the tag with respect to 55 the goods and the latter for driving the tag spurs through and clinching them under the goods.

We have also aimed to provide a staple tag-affixing machine of novel construction 60 capable of being manufactured at a comparatively low cost.

Other objects and attendant advantages 65 will be appreciated by those familiar with this art as the invention becomes better understood by reference to the following description when considered in connection with the accompanying drawings, in which—

Figure 1 is a side elevation of a staple tag-affixing machine embodying our invention; 70

Fig. 2, a front elevation of the machine;

Fig. 3, a top view thereof;

Fig. 4, a vertical sectional view taken substantially on the line 4—4 of Fig. 2, showing 75 the machine in normal position;

Figs. 5 and 6, fragmentary sectional views similar to Fig. 4, but showing the parts in different operated positions;

Fig. 7, a fragmentary face view of the 80 anvil end of the operating lever;

Fig. 8, a front view of the parts shown in Fig. 7;

Fig. 9, a fragmentary sectional view taken substantially on the line 9—9 of Fig. 7; and 85

Fig. 10, a perspective view of a staple laundry tag.

The operating parts of the machine are supported by a standard designated generally by character 12, in turn mounted upon 90 a base 13 preferably in the form of a tag receptacle. The staple tag shown in Fig. 10 has an elongated fabric mark-receiving body 14 and a pair of spurs or staples 15 at each end. While the present machine is designed 95 to affix a staple tag of this particular type, it should be understood that the principles of this invention have a broader application and are adaptable to other long-spur tags or similar articles having attaching spurs. 100

Briefly stated, the operation is to place a tag 16, spurs down, on a pivotal seat 17 in a tag carrier designated by character 18; then place the goods or material 19 over an anvil structure at the outer end of a lever 105 21, as shown in Fig. 4, holding the goods by the thumbs of both hands over the thumb rests 22 projecting laterally from said lever;

and then pressing downwardly on said thumb rests in a quick action. This swings the lever 21 downwardly and through means which will be presently described, causes the outer end of the tag carrier to descend and engage the goods 19 so as to hold it in position and provide a suitable guide for the tag which will by the said action be forced by means of a hammer designated by character 23, through the tag carrier until the spurs 15 have pierced the goods and been clinched thereunder. Upon releasing the lever 21, a spring 24 returns all of the parts to normal position.

15 The main lever 21 fulcrumed at 25 between the spaced sides 26 of the standard 12 is constantly urged in a counterclockwise direction by the contractile spring 24. Such movement is arrested by stationary stop pins 27 engaged by the pivoted end of the tag carrier 18, which acting through the hammer lever as will be presently described, determines the normal or idle position of the main lever. The outer or free end 28 of the main lever carries a pair of laterally spaced anvils 29, which are in effect integral with the main lever and have dished faces, that is, front and rear portions 31 of the anvil inclined downwardly toward the central portion which is comparatively flat. These anvils project through openings 32 in a goods-receiving plate 33 which is movably mounted on the lever end 28, being retained in position by a stop bolt 34 and constantly urged by expansion springs 35 to an upper position, shown in Figs. 2, 4, 8 and 9. In this position, the top flat surface of the plate 33 is slightly above the top surface of the anvils 29. It will be observed from Fig. 40 that the opposed sides 36 of the openings 32 converge from each end and that the anvils 29 correspond in shape to these openings. Upstanding stops 37 on the lever 21 limit the inward position of the goods 19.

45 The hammer 23 is part of a weighted lever 38 pivotally mounted at 39 upon and between the sides 26 of the standard 12. By means of links 41 pivotally connecting the main lever 21 and hammer lever 38, the latter will be swung in a clockwise direction at a considerably faster speed than the main lever when this lever is depressed by the hand operation above referred to. The outer end of the hammer lever has a weight 55 42 which adds considerable momentum and driving force to the blow.

60 The tag carrier 18 also pivotally mounted on the pin 39 and straddling the lever 38, has a bifurcated outer end, the spaced sides 43 of which are formed at their inner sides with tag grooves or guides 44. The tag seat member 16 mentioned above is pivoted at 45 between the sides 43 and constantly urged in a counter-clockwise direction by a coiled spring 46, to a position limited by the stop

47, as shown in Fig. 4. This seat is adapted to be swung in a clockwise direction entirely out of the space between the guides 44 to give way to the hammer 23 and withdraw from the tag. A flat spring 48 carried by the hammer lever 38 urges the tag carrier in a clockwise direction until stopped by the pins 49 on the outer sides of the links 41, as best shown in Fig. 1. It will be observed from Figs. 2 and 3, that the head of the hammer 23 is full width to fit between the grooves 44, and as shown in Fig. 4, is of arcuate shape corresponding to the arc of the grooves 44, concentric with the pivot 39.

10 The operation is as follows: The staple tag 16 will be placed on the seat 17 which is of such width as to be entirely disposed between the spurs 15, leaving these spurs projected down. The goods 19 held in both hands will be positioned on the plate 33, and with the thumbs over the thumb rests 22, the latter will be depressed. This pressure swings the lever 21 downwardly and the latter through the links 41, will swing the hammer forwardly to affix the tag. It will be observed that the instant the main lever 21 starts to descend the stop pins 49 will be withdrawn from the tag carrier 18 allowing the spring 48 to move the tag carrier downwardly into engagement with the goods, thereby holding the same and properly positioning the tag, the spurs of which are to be driven through the goods.

15 The hammer descends and engages the tag throughout its length as shown in Fig. 5, forcing the seat 17 out of its path, as shown in Fig. 6. In other words, the tag will be carried down through the guide provided by the ways 44, squarely upon the goods so that all of the four spurs enter the 105 goods at the same instant. Since the goods is supported by the plate 33 in a plane slightly above the faces of the anvils the spurs will pass entirely through the goods and upon striking the curved surfaces 31 110 will be turned inwardly. In the event that the spurs deflect laterally, they will be guided by the adjacent walls 36 substantially into alignment crosswise of the tag. It will thus be seen that before the fabric 115 body 14 of the tag reaches the plate 33 the spurs will be projected through the goods and turned inwardly. As the tag is pressed down by the hammer, the plate 33 will be depressed until the full pressure of the hammer is brought to bear on the spurs resting on the anvil faces. This construction insures passage of the spurs completely through the goods and the directing and guidance of the spurs inwardly in a predetermined path and finally a forcible compressing blow which securely clinches the spurs and the tag to the goods. As a result of the action of the anvil faces 31, the points of the spurs will be curved inwardly and up- 130

wardly and so embedded in the body of the goods as to be thoroughly protected against any danger from scratching or marring. It should be noted that in affixing the tag the 5 best results are obtained by pressing down on the main lever in a quick movement, thereby imparting a rapid movement to the hammer, which due to its weighted construction imparts a forcible striking blow to the

10 tag. In view of the fact that the machine is portable and the operating parts are supported entirely by the base, they have been arranged forwardly overhanging the base so that the rebound of the hammer upon 15 releasing the main lever after affixing a tag will be effectually counteracted.

It is believed that the foregoing conveys 20 a clear understanding of the objects prefaced above, and while we have illustrated 25 but a single working embodiment, it should be understood that various changes might be made in the construction and arrangement without departing from the spirit and scope of the invention as expressed in the 25 appended claims, in which—

We claim:

1. In a tag-affixing machine, the combination 30 of a swinging lever provided with an anvil, normally held in position to receive the goods, a tag-carrier and guide for receiving a tag and holding it away from the anvil, a hammer for driving the spurs of the tag through the goods, and means operated by swinging movement of the anvil-lever 35 for moving the tag-carrier and guide into operative relation with the anvil and for moving the hammer to force the spurs through the goods and fasten the tag thereto.

2. In a tag affixing machine, the combination 40 of an anvil on which the goods is adapted to be placed, a hammer, a tag-carrier and guide having a pivotal seat upon which a staple tag is adapted to be supported in a plane transverse to the movement of the hammer, and means for moving said tag-carrier 45 from a position remote from the goods to one engaging the goods and holding it against the anvil, said hammer and tag-carrier being so relatively arranged and the hammer being 50 so operated as to move in the path of said pivotal seat, whereby said seat will be swung out of the path of the hammer and the tag will be carried with the hammer through the guiding portion of the tag-carrier and whereby the hammer will force the spurs 55 through the goods for affixing the tag thereto.

3. In a tag-affixing machine, the combination 60 of a main lever equipped at its free end with an anvil, means manually operable for moving the lever, a tag-carrier and a hammer concentrically mounted intermediate the ends of the lever, the tag-carrier being interposed between the hammer and the 65 anvil and adapted to carry a tag in the path

of the hammer and in a position to be affixed to goods positioned on the main lever over the anvil, and means operated by movement of the main lever for moving the tag-carrier into engagement with the goods for 70 holding the same against displacement and for moving the hammer in a striking blow to force the spurs of the tag through the goods and clinch the tag thereto.

4. In a tag-affixing machine, the combination 75 of a lever provided at one end with an anvil, a swinging tag carrier above said anvil equipped with a pivotal seat for holding a tag, a hammer adapted for engaging the tag, moving it from said seat, and forcing the tag spurs through the goods on said anvil, and means operated by said lever for operating the hammer to affix the tag.

5. In a tag-affixing machine, the combination 80 of a lever provided at one end with an anvil, a swinging tag carrier above said anvil equipped with a pivotal seat for holding a tag, a hammer adapted for engaging the tag, moving it from said seat, and forcing the tag spurs through the goods on said 85 anvil, and means operated by said lever for operating the hammer to affix the tag, and for causing the tag carrier to hold the goods against said lever prior to the time the spurs 90 pierce the goods.

6. In a machine of the character described, the combination of a part having a pair of laterally spaced upstanding anvils, a goods-receiving plate yieldingly supported on said part and having openings fitting 95 said anvils and through which the latter are adapted to pass by depressing the plate, the opposed sides of each opening converging from each end, and the anvils being correspondingly shaped, and means for driving 100 the spurs of a staple tag downwardly through goods supported on said plate with the staples in alignment with said anvils for affixing the tag to the goods.

7. In a machine of the character described, the combination of a lever having a pair of laterally spaced upstanding anvils, a goods-receiving plate yieldingly supported on said lever and having openings fitting 110 said anvils and through which the latter are adapted to pass by depressing the plate, a thumb rest on each side of the lever adapted to be operated in a tag-affixing movement, and means operated by such movement of the lever for forcing the spurs 115 of a staple tag through the goods on said plate to thereby affix the staple to the goods.

8. In a machine of the character described, the combination of a lever equipped at one end with a goods-receiving part and 120 with thumb rests at each side of said part, a swinging tag-carrier adapted to support a tag above the goods, a weighted hammer, and means operated by said lever upon depression of said thumb rests to move the tag 125 130

carrier into operative relation to the goods-receiving part and to cause said hammer to affix the tag to the goods.

9. In a machine of the character described, the combination of a goods-receiving part, a tag carrier and a hammer each pivotally mounted, and means connecting said pivoted parts for causing them to move from a tag and goods-receiving position to a tag-affixing position by pressure applied to the goods-receiving part.

10. In a machine of the character described, the combination of a goods-receiving part, a tag-carrier movable from a tag-receiving position remote from said part to one in proximity thereto for guiding the tag just prior to its application to the goods, a pivotal seat on said carrier adapted to support a staple tag in the path of a hammer, a hammer adapted to move through said tag-carrier and to carry the interposed tag before it and force the spurs through the goods, said pivotal seat swinging to a retracted position by said action of the hammer, and means for returning said seat to its normal position after the hammer has been withdrawn from the tag-carriers.

11. In a machine of the character described, the combination of a lever having an anvil, a pivoted tag carrier adapted to carry a staple tag above the anvil, a pivoted weighted hammer adapted to strike said tag and force its spurs through goods positioned over said anvil, and means operated by said lever by depression of the anvil end thereof to move the tag carrier into co-op-

erative relation with the anvil and to swing the hammer in a tag-affixing movement.

12. In a machine of the character described, the combination of a lever adapted to be manually depressed at one end and equipped at such end with stationary anvils and a depressible goods-supporting part, means for supporting a staple tag above said anvils, a pivoted weighted hammer, and means operated by said lever by depression thereof for moving said hammer to drive the tag spurs through goods on said goods-receiving part, thereby depressing the latter and clinching the spurs beneath the goods by engagement of said spurs with said anvils.

13. In a machine of the character described, the combination of a lever adapted to be manually depressed at one end and equipped at such end with a goods-receiving part and an anvil, a tag carrier normally supported in spaced relation above said goods-receiving part and equipped with a pivotal seat adapted for holding a staple tag, a weighted hammer adapted for striking the tag on said seat, removing it therefrom and forcing the tag spurs through goods on said goods-receiving part, means operated by depression of said lever for operating the hammer in a tag-affixing movement, and means operated by the hammer for moving the tag-carrier into engagement with the goods before the tag spurs pierce the goods.

WILLIAM BORCHERT.
